UNITED STATES PATENT OFFICE.

LUCIUS T. GIBBS, OF HEMPSTEAD, NEW YORK.

INTERNAL-COMBUSTION ENGINE.

No. 872,336.

Specification of Letters Patent.

Patented Dec. 3, 1907.

Application filed May 2, 1906. Serial No. 314,742.

To all whom it may concern:

Be it known that I, LUCIUS T. GIBBS, a citizen of the United States, residing at Hempstead, Long Island, in the State of New York, have invented certain new and useful Improvements in Internal-Combustion Engines, of which the following is a specification, reference being had to the accompanying drawing, forming a part hereof.

10 This invention relates to internal combustion engines of the two-cycle type in which an exhaust port of the working cylinder is opened as the piston approaches the forward limit of its stroke and an inlet port for the 15 fresh charge is opened at the same time or immediately thereafter. In the operation of such engines, as ordinarily constructed, it usually happens either that the burned gases are insufficiently cleared out of the working 20 cylinder or that more or less of the new charge is wasted in expelling the burned gases. In either case the efficiency of the engine suffers.

By the present invention it has been 25 sought to provide, in engines of the type referred to, means for more effectively clearing out the burned gases after each explosion without waste of the fresh charge. In attaining this object a vacuum chamber, that 30 is, a means whereby the pressure is reduced, is connected with the working cylinder through a valve which is opened at the proper instant in order that the burned gases may be drawn out of the working cylinder, 35 the exhaust port being closed meanwhile, so that the burned gases already expelled are not drawn back into the cylinder. The subsidiary exhaust valve, moreover, is so located, preferably in the head of the cylinder, 40 as to cause the withdrawal of the burned gases to effect or facilitate the introduction of the fresh charge behind them. The invention will be more fully explained herein- 45 after with reference to the accompanying drawing which represents, partly in elevation and partly in vertical section, and more or less diagrammatically, an engine to which the present improvement is applied.

The engine represented in the drawing 50 comprises, as usual, a cylinder *a* provided with an exhaust port *a'* and an inlet port *a²*, both of which are adapted to be uncovered, the exhaust port slightly in advance of the inlet port, by the trunk piston *b* as it approaches the limit of its forward stroke. 55 The piston is connected, as usual, by the

pitman *c*, with the usual crank shaft *d*. A carburetor *e* of ordinary construction is represented as connected with the inlet port *a²*, so that the explosive charge shall be formed 60 and introduced into the cylinder as the inlet port *a²* is opened. The piston *b* is provided with a projecting lip *f*, having an aperture *f'* in line with port *a'*, so that as the piston approaches the limit of its forward stroke the 65 exhaust port *a'* first communicates with the interior of the cylinder through the port or aperture *f'* and is then closed by the lip.

At a suitable point in the cylinder, preferably in the head thereof, is provided a subsidiary valve controlled exhaust port *g*, which communicates with a vacuum chamber. As shown, the port *g* communicates with a vacuum tank *h* which is in turn connected with a vacuum pump *i* operated by 75 an eccentric *k* on the shaft *d*. The port *g* is controlled by an inwardly opening valve *l* which is opened at the proper instant by any suitable means. As shown, the valve stem *l* has applied thereto a spring *l²* which holds 80 the valve normally in its closed position, and a roller *l³* which is acted upon to open the valve at the required instant by a cam *m* on shaft *m'* which may be driven through beveled gears *m²*, the shaft *n*, and beveled gears 85 *n'* from the crank shaft *d*.

It will now be understood that in the operation of the engine, a partial vacuum having been established in the tank *h*, the piston *b*, as it approaches the forward limit of its 90 stroke, first opens the exhaust port *a'* permitting the burned gases in the cylinder to escape under their own pressure. The continued forward movement of the piston then closes the exhaust port *a'* through the action 95 of the lip *f* and opens the inlet port *a²*, permitting the entrance of the fresh charge through the establishment in the cylinder of a partial vacuum, through the opening at that instant of the subsidiary exhaust port *g*. 100 A partial vacuum being maintained in the tank *h*, burned gases which remain in the cylinder are immediately drawn out of the same and, the pressure in the cylinder being thereby reduced, the fresh charge is drawn 105 into the cylinder through the inlet port, following the burned gases in their withdrawal. The valve *l* should remain open long enough not only to insure the removal of the greater portion of the burned gases from the cylinder 110 but to insure also the filling of the same with the fresh charge. This takes place while the

exhaust port a' is closed by the lip f . The exhaust port is again opened as the piston begins its rearward stroke, but as the pressure in the cylinder is then substantially atmospheric there is practically no escape of any portion of the fresh charge through the exhaust port.

It will be obvious that the subsidiary exhaust port may be located otherwise than as shown and that the vacuum may be maintained and the valve operated by any suitable means, as well as that the construction of the engine in other respects may be of any suitable character, other than as shown in the drawing.

I claim as my invention—

1. In an internal combustion engine, the combination of a cylinder, a piston, said cylinder having inlet and exhaust ports uncovered by the piston as it approaches the limit of its forward stroke, the piston having an apertured lip whereby the exhaust port after being opened, is closed during the continued forward movement of the piston, and means to withdraw the burned gases from the cylinder while the exhaust port is closed and the inlet port is opened.

2. In an internal combustion engine, the combination of a cylinder, a piston, the cylinder having inlet and exhaust ports uncovered by the piston as it approaches the limit of its forward stroke, a subsidiary exhaust port independent of the main exhaust port, means to close the main exhaust port after it has been opened during the continued forward movement of the piston, a valve to control the subsidiary exhaust port, means to open said valve while the main exhaust port is closed, and a vacuum chamber connected with said subsidiary exhaust port.

3. In an internal combustion engine, the combination of a cylinder, a piston, the cyl-

inder having inlet and exhaust ports uncovered by the piston as it approaches the limit of its forward stroke and a subsidiary exhaust port, the piston having an apertured lip to close the main exhaust port after the same is opened in the continued forward movement of the piston, a valve to control the subsidiary exhaust port, means to open said valve while the main exhaust port is closed and a vacuum chamber connected with the subsidiary exhaust port.

4. In an internal combustion engine, the combination of a cylinder, a piston, the cylinder having inlet and exhaust ports, means whereby said ports are opened as the piston approaches the forward limit of its stroke, a subsidiary exhaust port at the head end of the cylinder, a valve for controlling said subsidiary exhaust port, means for operating said valve to open said subsidiary exhaust port as the piston approaches the forward limit of its stroke, and a vacuum chamber connected with the subsidiary exhaust port.

5. In an internal combustion engine, the combination of a cylinder, a piston, the cylinder having inlet and exhaust ports, means whereby said ports are opened as the piston approaches the forward limit of its stroke, a subsidiary exhaust port at the head end of the cylinder, a valve for controlling said subsidiary exhaust port, means for operating said valve to open said subsidiary exhaust port as the piston approaches the forward limits of its stroke and while the main exhaust port is closed, and a vacuum chamber connected with the subsidiary exhaust port.

This specification signed and witnessed this 26th day of April, A. D. 1906.

LUCIUS T. GIBBS.
